US00D908489S

(12) **United States Design Patent** (10) Patent No.: **US D908,489 S**
(45) Date of Patent: ** Jan. 26, 2021

(54) **HERBICIDE SPRAYER LOW PRESSURE FOAM TIP**

(71) Applicant: **Ross Lazarov**, Prior Lake, MN (US)

(72) Inventor: **Ross Lazarov**, Prior Lake, MN (US)

(**) Term: **15 Years**

(21) Appl. No.: **29/700,525**

(22) Filed: **Aug. 2, 2019**

(51) LOC (13) Cl. **09-01**

(52) U.S. Cl.

USPC **D9/445**; D23/249

(58) **Field of Classification Search**

CLAIM

The ornamental design for an herbicide sprayer low pressure foam tip, as shown and described.

DESCRIPTION

FIG. 1 is a front top perspective view of the herbicide sprayer low pressure foam tip of the present invention;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof; and,

FIG. 8 is a back bottom perspective view thereof.

(Continued)

The dot-dash lines represent the boundaries of the claim and form no part thereof.
